HENRY CLAY WADE, OF NEW YORK, N. Y., ASSIGNOR TO HYDRO CARBON GAS COMPANY, A CORPORATION OF DELAWARE.

HYDROCARBON-BURNER.

1,125,777.

Specification of Letters Patent. Patented Jan. 19, 1915.

Application filed September 9, 1910. Serial No. 581,163.

To all whom it may concern:

Be it known that I, HENRY CLAY WADE, a citizen of the United States, and a resident of New York, county and State of New York, have invented certain new and useful Improvements in Hydrocarbon-Burners, of which the following is a full, clear, and exact description.

This invention relates more particularly to stoves and burners adapted for burning kerosene oil.

The primary object of the invention is to provide simple and efficient means in which a fluid, as kerosene oil, may be caused 15 to pass to the burner and there vaporize and the vaporized fluid caused to mix properly with air in such a way that the said mixture will produce an effective blue or heat flame, at the same time provide a 20 burner which will remain free from carbon or other objectionable matter which is likely to reduce the efficiency of the burner and cause the same to smoke, thus overcoming many of the objections incident to 25 oil stoves and burners heretofore proposed for vaporizing and burning kerosene oil.

Another object of the invention is to provide a burner which is simple in construction, which may be readily made and assembled, and which may be employed in 30 various connections.

A further object of the invention is to provide simple means whereby the kerosene oil for the initial heater and the burner 35 may be supplied from the same source.

A still further object of the invention is to provide a burner which is particularly adapted to produce a blue heat flame, and to provide means whereby the oil may be 40 positively driven to the burner in such a way as to avoid all likelihood of accident, and which means may be easily controlled.

With these and other objects in view, the invention will be hereinafter more particularly described with reference to the accompanying drawings, which form a part 45 of this specification, and will then be pointed out in the claims at the end of the description.

50 In the drawings, Figure 1 is a front elevation, partly in section, of one form of means embodying my invention. Fig. 2 is a side elevation. Fig. 3 is an enlarged vertical section of one form of burner which

may be employed. Fig. 4 is a plan view 55 of the burner. Fig. 5 is a sectional plan view through the burner, taken on the line V—V of Fig. 3. Fig. 6 is an enlarged transverse section, taken on the line VI—VI of Fig. 3. Fig. 7 is an enlarged section, 60 taken on the line VII—VII of Fig. 3. Fig. 8 is an enlarged sectional view, partly in elevation, of the burner and the initial heating means. Fig. 9 is an enlarged section of the initial heating means. Fig. 10 is a 65 sectional view, taken on the line X—X of Fig. 9. Fig. 11 is a sectional view, taken on the line XI—XI of Fig. 9; and Fig. 12 shows how two initial heating devices may be employed so as to heat the burner from 70 opposite sides to initially vaporize the oil and heat the burner.

While I show a stove and a burner of one form and in which the source of supply is arranged in a particular way, it will 75 be understood that the burner may be used for any purpose and in any connection, and that some of the parts may be differently arranged or constructed, or some of the parts dispensed with, if desired, without 80 departing from the spirit and scope of my invention, as defined and set forth in the appended claims.

The frame or body of the stove 10 or other support may be of any suitable construction 85 and said body may have means, as the plates 11, on which receptacles may be placed to be heated, and under the stove or in any other suitable location may be arranged a tank or reservoir 12 in which the kerosene 90 oil or fluid to be vaporized is located. This reservoir may be held to the lower portion of the stove by straps 13, or otherwise, and at one side of the stove may be arranged a pipe or connection 14, the outer end of 95 which may be closed by a cap, as 16. The cap 16 may be provided with a cock or valve 17, and when the cap is removed, the cock 17 is also removed therewith and will permit the tank to be filled through said pipe 100 or connection 14, the purpose of the cock being to permit air within the tank or reservoir to escape therefrom. The pipe 14 has its inner end arranged above the normal oil level, and connected to said pipe is a 105 pipe 18 which leads to an air pump 19. This pump 19 may be of the usual hand-operated kind and may be secured to the

side of the stove by the straps 20. A handle 21 may be pivoted to the side of the stove, as at 22, and may be connected by the rod 23 to the piston of the pump, and 5 may also have its handle portion, as 23^a, extending forward toward the front of the stove within easy reach, so that said handle may be operated to force air under pressure into the tank or reservoir 12, there being a 10 gage, as 24, by which the pressure within the tank may be readily ascertained.

A pipe 25 is secured to the tank so that its end 26 extends inward below the level of the oil, and at a convenient point above the 15 tank is located a valve 27 of any suitable kind by which the oil in the pipe 26 may be readily cut off, it being understood that the oil will be forced through the pipe 26 by means of the air pressure within the tank 20 above the oil. At the upper portion of the pipe 25 is a burner 28. As shown in the drawings, there are two burners and connections therefor provided for heating purposes, and a burner for lighting purposes 25 to be referred to hereinafter, though a single burner may be employed or the number of burners may be varied according to the use to which the same is put, and the size may vary according to the body to be 30 heated or the use to which the burner is applied.

The burner 28 may have a casing or supporting member 29 having a pipe or tubular portion 30 which may be secured by a 35 coupling, as 31, to the upper portion of the pipe 25, and this casing has a stem portion or member, as 32, provided with a projecting threaded boss 33 to which one end of the tube or member 34 is secured. This member 34 is threaded at its upper end and engaging said threads is a boss or base portion 35 of the burner proper 36. A part or extension 37 projects from the boss 33 and said extension is somewhat smaller in cross-section than the interior of the tube 34 so as to provide a space or chamber 38 around said extension, and in this space is a wire 40 gauze 39 or other heat conducting means through which the oil must pass before it 45 reaches the burner, and which gauze serves to break up the oil into fine particles. The stem portion 29 is arranged in parallel relation to the part 30 of the casing and is connected therewith by the tubular portion 40. 50 A passage 41 extends through the connection 40 and this passage communicates with the tubular part 30 and the passage 42 in the stem member 29, and through which the oil passes to the chamber 38 around and 55 about the gauze 39. A cap 43 is held to the outer end of the tube 34 and in this cap are a plurality of openings, as 44, through 60 which the vaporized oil, passes, and above the cap 43 is a plug 45 having a threaded outer surface engaging a threaded opening

in the part 35 and having means, as recesses 46, by which the plug may be rotated, thus serving to hold the cap 43 in place. An opening 47 of preferably very small cross-section is formed substantially 70 centrally of the plug or member 45 and under said opening is a chamber, as 48, above the end of the extension 37 through which the vapor may pass to the opening 47, and in alignment with said opening is a 75 relatively small pin or device 49 which is arranged on the outer end of the longitudinally-movable stem or rod 50 so that by the movement of said rod, the pin or device 49 may be caused to pass through the opening 47 thereby serving to clean the same and to 80 keep the opening free of any carbon or any matter that might collect to close said opening, the said pin serving also in a measure to act as a valve to prevent the vapor passing through said small opening. The stem or rod 50 has one end threaded, as at 51, and on said threaded end is a finger knob or handle 52 by which the said rod may be rotated. The threaded end 51 engages a 85 threaded aperture 53 in a stuffing box 54, and this stuffing box 54 has a threaded portion, as 55, to engage a threaded recess, as 56, in which may be packing, as 57, by which 90 leakage past the rod or device 50 is prevented. By this means a very effective supply for the oil is provided and when vaporized, as will be hereinafter described, the 95 said vapor may be properly controlled and at the same time the opening through the 100 plug 45 is prevented from becoming obstructed by any objectionable material.

The burner proper has a cup-shaped member 58 formed integral with the boss or part 35, and in said member 58 are a plurality of 105 openings 59 through which air may pass so as to commingle with the vapor as it passes through the small opening 47. The upper portion of the member 58 is recessed to form a shoulder 60 and resting upon this shoulder is a cap or member 61. This cap or member has a threaded opening, and this threaded opening is engaged by the threaded end of a tapered tubular stem or part 62, the upper portion of which is contracted 110 and provided with a surrounding flange, as 63, forming an inverted cup-like device or member, the downwardly-extending wall of which rests upon the upper surface of the cap 61, there being a flange or bead, as 64, 115 serving to guide and hold the device in position. An inverted cup-shaped member or device 65 is located above and concentric with the cup-like member 63 and is somewhat larger than the same so as to provide 120 a mixing chamber 66 for the air and vapor, and said cup-like member has a downwardly-extending wall or flange 67 provided with a plurality of openings 68 through 125 which the vapor and air escape to be 130

lighted. The flange 67 is separated somewhat from the flange or wall 63 and said cup-shaped device is centered by means of a flange 69 on the head or cap 61, and adjacent to the flange 67 is an outwardly flared flange or part 70, substantially bell-shaped, formed as a part of the cup-shaped member 58, against which the vapor strikes and which causes the flame to spread upwardly and outwardly substantially bell-like. The vapor and air are thus properly and thoroughly mixed and the parts are so constructed that when once heated, the heat will be conveyed back to the part where the oil enters the space 38 and will effectively vaporize the same so that a perfect heat flame is produced free of carbon so that the burner and parts thereof remain perfectly clean while in use.

It is very desirable that effective means be provided for heating the burner initially to vaporize the fluid, and that this be done in such a way so as not to be objectionable to those using the burner, and also it is desirable that the same source of supply of fluid or oil for the burner be utilized to supply the initial heating means. As shown, Figs. 8 to 11, a device 71 is provided which has a part thereof located adjacent to the burner proper, and this device has a tubular part 72, the lower end of which is threaded and secured by a bushing 73 to the upper part of the tank so that air may pass within said tubular portion. The upper portion of the tube 72 may be bent so as to form an angle 74 and has its upper end threaded. A valve casing 75 is secured to the upper end 74 and in said casing is a valve 76 which is adapted to control an opening 77 in said casing in the usual way. The valve is provided with an opening 78 which is adapted to be brought into communication with the opening 77 of the valve casing and with a chamber, as 79, at one side of the valve, and a larger chamber 80 at the other side of the valve within said casing, and said chamber 79 tapers toward the opening 77 and communicates with a plurality of openings 81 arranged in the end 74 of the tube 72. A small tube, as 82, has one end held to the outer end of the tube 72, and said smaller tube extends within the tank and has its lower end open so that the oil, by reason of the air pressure above the same may be forced in a fine stream through said tube 82. A nozzle portion 83 is formed on the end of the tube 72 above the tube 82 for the oil so that the effect of the air meeting the oil at the mouth of the nozzle 83 forms an atomizer causing the mixture in the form of a spray to pass through the opening 78 of the valve, through the chamber 82 and out through an opening 85 formed in the rounded or substantially closed end 86 of the casing 75. The casing 75 may have an enlarged

tubular member 87 secured thereto, as by the ribs or inwardly-projecting portions 88, and said member 87 is relatively larger than the casing 75 so as to provide a chamber about the same in order that air may enter 70 the lower open end 89 and commingle with the atomized spray to be ignited by means of a match or otherwise, a convenient means for lighting the spray being through an opening 89 in the member 87. The lighted spray in the form of a heat flame will quickly heat the lower part of the cup-shaped member 58 of the burner proper, and this will cause the upper portion of the burner to be heated and also the heat to be 80 transmitted to the lower portion of the same, so that the oil before passing to the opening 47 will be thoroughly vaporized. By opening the cock 17, the air will escape from the reservoir and this will stop the 85 flow of the oil to the burner or burners and to the atomizer, and this means may be used with or independent of the valve 27.

It will be understood that while the initial heating device, which is in the form of an 90 atomizer, is a most effective means for initially heating the burner, other means may be employed if desired, and instead of a single atomizer or initial heating device on one side of the burner, there may be two, as shown in 95 Fig. 12, or a number of them so arranged to heat the burner from opposite sides thereof. In this case the tube 72 has a branch 90 and within said branch is a small tube 91 which connects with the pipe 82 so that air and oil 100 may be supplied to the atomizer device 92 which is constructed substantially the same as the device 71.

The burner is not only adapted for heating purposes, but may be also used in connection with a lamp or other lighting device. As shown, a lamp 93 is mounted upon the stove to light the room and out of the way of the heating portion thereof, and said lamp has a burner substantially the same as that already described and similar to that shown at 71, the oil and air being supplied thereto as already described. Where the burner is used in connection with a lamp, a mantle 94 of the usual kind may be made to surround the burner or portion thereof, and said lamp may have a chimney as 95 with other attachments, as is usual with devices of this character.

From the foregoing it will be seen that simple and efficient means is provided whereby a burner may generate vapor from kerosene oil and unite with air supplied thereto to produce an effective heat flame; that said burner is simple in construction and may be readily made and assembled; that simple initial heating means is provided whereby the burner may be made to vaporize the oil; that said burner may be used for various purposes whether lighting 120

or heating; and that said burner is so constructed that it will remain perfectly clean and free from carbon deposit while in use.

Having thus described my invention, I claim as new and desire to secure by Letters Patent:

1. A device of the character described, comprising a burner proper, a casing having an extension of heavy metal, a tubular member located around said extension and forming a chamber therebetween and connected to said burner, a cap fitting over said tubular member and having a plurality of openings therethrough, a plug resting on said cap and having a small passage therethrough and forming a chamber underneath said plug above the cap, and a rod adjustable in said extension of the casing and having a handle at one end and a needle portion at the other end adapted to pass through the opening in the plug.

2. A device of the character described, comprising a burner proper, a casing having a cored extension of substantially heavy metal, a tubular member located around said extension and forming a chamber therebetween and connected to the burner, means located in the chamber for dividing a fluid body, a cap fitting over said tubular member and having a plurality of openings therethrough, a plug resting on said cap and having a very small passage therethrough and forming a chamber having a conical upper portion and underneath said plug above the cap, and a rod adjustable in said casing and having means adapted to pass through the opening in the plug.

3. A device of the character described, comprising a burner proper, a casing having a tubular extension of heavy metal, a tubular member located around said extension and forming a chamber therebetween and connected to said burner, wire gauze surrounding the tubular extension located in the chamber to divide a fluid body, a cap fitting over said tubular member and having

a plurality of openings therethrough, a plug resting on said cap and having a small passage therethrough and forming a chamber underneath said plug above the cap, and a rod adjustable in said casing and having a handle portion and a needle portion adapted to pass through the opening in the plug.

4. The combination with a source of fluid supply, of a burner comprising a casing communicating with said source of supply, said casing having an extension, a tubular member arranged around said extension and forming a chamber within the same, wire gauze arranged within said chamber and surrounding said extension, a cap fitting over said tubular member and having a plurality of openings therein communicating with the chamber in which the gauze is located, a plug located over the cap and having a relatively small opening therethrough, a device movable lengthwise of the casing and having a part thereof entering the opening to keep the same clean and through which a gaseous vapor may pass, and means for mixing air with the vapor.

5. A burner comprising a casing having an extension, a tubular member arranged around said extension forming a chamber within the same, wire gauze arranged within said chamber and surrounding said extension, said casing having a passage adapted to communicate with a source of fluid supply, a cap fitting over said tubular member and having a plurality of openings therein communicating with the chamber in which the gauze is located, a plug located over the cap and having a relatively small opening therethrough, and means entering the opening to keep the same clean.

This specification signed and witnessed this 7th day of September A. D. 1910.

HENRY CLAY WADE.
